LEAF SPRING

Frederick T. Rowland, Emsworth, and Willard F. Perdue, New Castle, Pa., assignors to Standard Steel Spring Company, Coraopolis, Pa., a corporation of Pennsylvania

Application July 24, 1946, Serial No. 685,854

10 Claims. (Cl. 267—47)

1

This invention relates to leaf springs. In order to keep the bending stresses low, particularly in the main spring leaf, it has been necessary to use thin leaves. The use of a thin main leaf reduces the strength of the main leaf eyes which are used for fastening the spring to the frame of a vehicle.

The present invention provides a construction in which the strength of the spring at the eyes is increased and in which the spring is prevented from collapsing in the event of failure of the main leaf at any point. Thus if there is failure of the main leaf at any point, the spring will continue to function as a unit until the broken main leaf can be replaced.

In the accompanying drawings which illustrate two embodiments of my invention,

Figure 1 is a partial vertical longitudinal elevation of the leaf spring;

Figure 2 is a horizontal longitudinal section taken on the line II—II of Figure 3;

Figure 3 is an enlarged partial longitudinal vertical section through the center of the spring;

Figure 4 is a partial longitudinal side elevation of a modified form of spring;

Figure 5 is a horizontal longitudinal section taken on the line V—V of Figure 6; and

Figure 6 is an enlarged partial side elevation of the spring shown in Figure 4.

Referring first to the embodiment shown in Figures 1 through 3, the spring comprises a main leaf 1 having at each end an eye 2 by means of which the spring can be pivoted to the frame of a vehicle. The main leaf 1 extends continuously from end to end and has an eye 2 at each end although for convenience only a portion of the entire spring has been shown. Located underneath the main leaf 1 is a wrapper leaf designated generally by the reference numeral 3. The wrapper leaf is made up of two separate sections 4 and 5. An eye 6 is formed at the outer end of each of the wrapper leaf sections 4 and 5, these eyes 6 acting to reinforce the eyes 2 of the main leaf 1. The inner end of each of the wrapper leaf sections 4 and 5 is reduced in horizontal sections to form a neck 7 and an enlarged head 8. A locking plate designated generally by the reference numeral 9 is located between the inner ends of the wrapper leaf sections 4 and 5. The locking plate 9 is provided with an opening 10 which receives a center bolt 11 passing through the whole spring assembly. The head 8 of each of the wrapper leaf sections 4 and 5 is received in a recess 12 formed in the locking plate. The recesses 12 are made sufficiently long in a direction endwise of the spring

2

to allow limited relative endwise movement of the heads 8 in the recesses in the normal operation of the spring such that the heads 8 do not contact either with the walls 13 of the recess or with the ears 14 of the locking plate. In other words, during the normal operation of the spring, relative endwise movement of the heads 8 with respect to the locking plate takes place due to the difference in deflection between the main leaf 1 and the wrapper leaf sections 4 and 5 but the locking plate does not actually act to lock the wrapper leaf sections 4 and 5. However, if the main leaf 1 should fail at any point the locking plate comes into operation and prevents collapsing of the spring. If the main leaf 1 fails at the left-hand side of the center bolt 11, the head 8 of the wrapper leaf section 4 will move to the left, this movement being limited by contact of the head 8 with the ears 14. Similarly, if the main leaf 1 fails at any point to the right of the center bolt 11, the wrapper leaf section 5 will move to the right until its head 8 will contact with the ears 14 of the locking plate. In either case the spring will not collapse but will continue to function thus preventing injury to other parts of the vehicle such as axle, drive shaft and steering mechanism, until the broken main leaf 1 can be replaced by a new leaf.

A rebound plate 15 is located above the main leaf 1 and several reinforcing leaves 16 are located below the locking plate 9 and the wrapper leaf sections 4 and 5. Accordingly, the wrapper leaf sections 4 and 5 slide between the main leaf 1 and the uppermost one of the reinforcing leaves 16. Free sliding movement of the wrapper leaf sections 4 and 5 is facilitated by making the locking plate 9 somewhat thicker than the wrapper leaf sections 4 and 5 so as to provide a space 17 as shown in Figure 3. In the embodiment of the spring which is shown, there are ten reinforcing leaves 16 but the number of such leaves may be varied in accordance with the desired characteristics of the spring.

Referring now to the embodiment shown in Figures 4, 5 and 6, the arrangement is generally similar to that shown in Figures 1 through 3 except that the locking plate 9 is omitted and the inner ends of the wrapper leaf sections are themselves formed so as to lock them together in the event of failure of the main leaf but to allow limited relative movement during normal operation of the spring. The main leaf 20 is provided with an eye 21 at each end. The wrapper leaf 22 is made of two sections 23 and 24, each of the sections having an eye 25 reinforcing the eye

21 of the main leaf. The inner end of the wrapper leaf section **23** is provided with a reduced neck portion **26** and an enlarged head **27**. The head **27** is received in a recess **28** formed in the inner end of the wrapper leaf section **24**, the recess **28** being sufficiently long to allow limited relative endwise motion of the head in the recess. The wrapper leaf section **24** is provided with ears **29** which limit movement of the head **27** upon failure of the main leaf **20**.

In order to provide free sliding movement of the wrapper leaf sections **23** and **24** between the main leaf **20** and the uppermost reinforcing leaf **30**, the wrapper leaf sections **23** and **24** are provided with slots **31** in each of which a freely movable button or roller **32** is received. The buttons **32** are not connected to any other part but are simply received in the slots **31**. A washer **33** fits around the center bolt **34**. The buttons **32** are slightly longer than the thickness of the wrapper leaf sections **23** and **24** so that they provide spaces **35** between the wrapper leaf sections and the main leaf **20** and the uppermost one of the reinforcing leaves **30**. The head **27** of the wrapper leaf section **23** is provided with a slot **36** in which the center bolt **34** is located thereby providing for endwise movement of the wrapper leaf section **23**. A rebound plate **37** is located above the main leaf **20**.

In the normal operation of the spring, the wrapper leaf sections **23** and **24** have endwise movement sufficient to compensate for the difference in deflection between the main leaf and the wrapper leaf sections but the wrapper leaf sections are not actually locked together. However, in the event of failure of the main leaf **20** at any point, the ears **29** limit the movement of the head **27** so that the spring will continue to function without collapsing until the broken main leaf can be replaced.

From the above description it can be seen that our invention provides an arrangement wherein the eyes of the main leaf are strengthened so that there is less likelihood of failure at the eyes. Furthermore, in the event of failure of the main leaf at any point, the spring will continue to function as a whole until the broken main leaf can be replaced.

The invention is not limited to the preferred embodiments but may be otherwise embodied or practiced within the scope of the following claims.

We claim:

1. In a leaf spring having a reinforcing leaf; a main leaf having an eye at each end, a pair of wrapper leaf sections having their outer ends provided with eyes which reinforce the eyes of the main leaf, the inner ends of the wrapper leaf sections being slidably disposed between the main leaf and reinforcing leaf, a locking plate located between the inner ends of the wrapper leaf sections, said locking plate allowing limited endwise movement of the inner ends of the wrapper leaf sections relative to each other during normal operation of the spring but positively limiting endwise movement of each of said inner ends upon failure of the main leaf at any point.

2. In a leaf spring having a reinforcing leaf; a main leaf having an eye at each end, a pair of wrapper leaf sections having their outer ends provided with eyes which reinforce the eyes of the main leaf, the inner ends of the wrapper leaf sections being slidably disposed between the main leaf and reinforcing leaf, the inner end of each wrapper leaf section having a neck and an en-

larged head, a locking plate located between the inner ends of the wrapper leaf sections, the locking plate having a pair of recesses each adapted to receive the head of a wrapper leaf section and allow limited relative movement during normal operation of the spring but positively limiting movement upon failure of the main leaf at any point.

3. In a leaf spring having a reinforcing leaf; a main leaf having an eye at each end, a pair of wrapper leaf sections having their outer ends provided with eyes which reinforce the eyes of the main leaf, the inner ends of the wrapper leaf sections being slidably disposed between the main leaf and reinforcing leaf, the inner end of each wrapper leaf section having a neck and an enlarged head, a locking plate located between the inner ends of the wrapper leaf sections, the locking plate having a pair of recesses each adapted to receive the head of a wrapper leaf section and allow limited relative movement during normal operation of the spring, the locking plate having means cooperating with the head of each wrapper leaf section for positively limiting movement of the heads upon failure of the main leaf at any point.

4. In a leaf spring having a reinforcing leaf; a main leaf having an eye at each end, a pair of wrapper leaf sections having their outer ends provided with eyes which reinforce the eyes of the main leaf, the inner ends of the wrapper leaf sections being slidably disposed between the main leaf and reinforcing leaf, the inner end of each wrapper leaf section having a neck and an enlarged head adjacent its inner end, the other of said wrapper leaf sections having adjacent its inner end a recess adapted to receive the head of said first mentioned wrapper leaf section and allow limited relative movement during normal operation of the spring but positively limiting movement upon failure of the main leaf at any point.

5. In a leaf spring having a reinforcing leaf; a main leaf having an eye at each end, a pair of wrapper leaf sections having their outer ends provided with eyes which reinforce the eyes of the main leaf, the inner ends of the wrapper leaf sections being slidably disposed between the main leaf and reinforcing leaf and locked to each other so as to allow limited endwise movement of the inner ends of the wrapper leaf sections relative to each other during normal operation of the spring but positively limiting endwise movement of each of said inner ends upon failure of the main leaf at any point, each of the wrapper leaf sections having a longitudinal slot adjacent its inner end and a spacing member freely slidable in each slot, said spacing members being longer than the thickness of the wrapper leaf sections.

6. In a leaf spring having a reinforcing leaf; a main leaf having an eye at each end, a pair of wrapper leaf sections having their outer ends provided with eyes which reinforce the eyes of the main leaf, the inner ends of the wrapper leaf sections being slidably disposed between the main leaf and reinforcing leaf, and means located entirely between the main leaf and the reinforcing leaf for positively limiting endwise movement of each of said inner ends away from the other upon failure of the main leaf at any point.

7. In a leaf spring having a reinforcing leaf; a main leaf having an eye at each end, a pair of wrapper leaf sections having their outer ends provided with eyes which reinforce the eyes of the main leaf, the inner ends of the wrapper leaf

sections being slidably disposed between the main leaf and reinforcing leaf, and means located entirely between the main leaf and the reinforcing leaf for positively limiting endwise movement of each of said inner ends away from the other upon failure of the main leaf at any point, said means comprising interengaging portions.

8. In a leaf spring having a reinforcing leaf; a main leaf having an eye at each end, a pair of wrapper leaf sections having their outer ends provided with eyes which reinforce the eyes of the main leaf; the inner ends of the wrapper leaf sections being slidably disposed between the main leaf and reinforcing leaf, and means located entirely between the main leaf and the reinforcing leaf for positively limiting endwise movement of each of said inner ends away from the other upon failure of the main leaf at any point, said means comprising at least one head and at least one pair of ears engaging said head.

9. In a leaf spring having a reinforcing leaf; a main leaf having an eye at each end, a pair of wrapper leaf sections having their outer ends provided with eyes which reinforce the eyes of the main leaf, the inner ends of the wrapper leaf sections being slidably disposed between the main leaf and reinforcing leaf, and means located entirely between the main leaf and the reinforcing leaf for positively limiting endwise movement of each of said inner ends away from the other upon failure of the main leaf at any point, said means comprising interengaging portions formed on said inner ends.

10. In a leaf spring having a reinforcing leaf;

a main leaf having an eye at each end, a pair of wrapper leaf sections having their outer ends provided with eyes which reinforce the eyes of the main leaf, the inner ends of the wrapper leaf sections being slidably disposed between the main leaf and reinforcing leaf, and means located entirely between the main leaf and the reinforcing leaf for positively limiting endwise movement of each of said inner ends away from the other upon failure of the main leaf at any point, said means comprising a locking plate located between the inner ends of the wrapper leaf sections and engaging each of said inner ends.
